C. L. GOODRUM,
NON-NUMERICAL SWITCH,
APPLICATION FILED SEPT. 11, 1916.

1,254,681.

Patented Jan. 29, 1918.

UNITED STATES PATENT OFFICE.

CHARLES L. GOODRUM, OF BROOKLYN, NEW YORK, ASSIGNOR TO WESTERN ELECTRIC COMPANY, INCORPORATED, OF NEW YORK, N. Y., A CORPORATION OF NEW YORK.

NON-NUMERICAL SWITCH.

1,254,681.

Specification of Letters Patent. Patented Jan. 29, 1918.

Application filed September 11, 1916. Serial No. 119,509.

To all whom it may concern:

Be it known that I, CHARLES L. GOODRUM, a citizen of the United States, residing at Brooklyn, in the county of Kings and State 5 of New York, have invented certain new and useful Improvements in Non-Numerical Switches, of which the following is a full, clear, concise, and exact description.

This invention relates to improvements in 10 non-numerical switches of the type employed in completing connections between calling and trunk lines.

It has formerly been customary in switches of this type to preselect an idle 15 trunk for a calling line before a call originates in that line. The present invention has for its purpose the preselection of a second idle trunk with a view of reducing the time interval in interconnecting calling and 20 trunk lines.

The drawings represent a perspective view of the improved switch. The frame and other unnecessary parts are omitted for clearness in illustration and description. 25 Certain operating circuits are associated with the mechanical parts to more clearly disclose their method of operation.

Referring to the drawing, 5 designates a shaft mounted in the supporting structure 30 (not shown). This shaft serves to support the contact makers or plungers 6, and their several controlling members. A U-shaped frame 8 comprising a relatively long vertical member and horizontally extending 35 arms 9 and 10 is rotatably mounted on the shaft 5. The vertical member 8 of the frame is provided with a rib 11, which extends at right angles to the vertical member 8, and lies in the direction of the shaft. The frame 40 is connected to a locking plate 12 by a sleeve 13 which also serves as a bearing on which these members rotate on the shaft. The locking plate 12 is sector-shaped, and its wide end is provided with notches 14. A 45 trip magnet 15 is provided with an armature 16 which is pivoted at 17. This armature is provided with extensions, one of which supports the catch 18, which is mounted to engage in notches 14 in the locking plate, and the other extension 19, which serves to close the contact springs 20 when the trip magnet 15 is energized. This magnet is provided with a locking coil 21, for a purpose herein later described. The shaft 55 is also provided with collars 22 which sup-

port a plurality of contact makers or plungers 6, each of which consists of a bar having an upturned end 23 and an enlarged end which broadens out to form a sector-shaped member 24. The upturned end of the plunger is provided with an insulated knob 25, adapted to enter the contact bank 26 of a structure commonly utilized in switches of this type. The shaft is passed through elongated apertures 27 in these plungers. The free end of the sector-shaped member 24 is provided with a notch 28, which is engaged by the rib 11, of the frame 7 when the plungers are drawn into engagement with the frame by the spring 29. An integral lug 30 on the plunger is engaged by the armature 31 of a magnet 32 to move the associated plunger into the contact bank when the magnet is energized. This magnet is provided with a pull down winding 33 and a holding coil 34. Sets of circuit-closing springs 35 are also controlled by the actuation of the armature 31. The upper end of the shaft rotatably supports an arm 36 which terminates at one of its ends in an angular extension 37 provided with an insulated knob 38. This knob serves to close the circuit-closing springs 39 which are carried by the U-shaped frame, whenever the arm 36 and the frame move into alinement. 45 The other end of arm 36 is provided with a brush 40 which engages contacts 41 of a master switch bank. The arm 36 is rigidly connected to locking plate 42 by a collar 43 which also serves as a bearing on which these members rotate on the shaft. The locking plate 42 is sector-shaped and is also provided with notches 43. These notches are engaged by a catch 44 carried on an extension of the armature 45 of a trip magnet 46. This armature has a second angular extension provided with an insulated knob 47 adapted to close the circuit-closing springs 48 when the armature is in its retracted position. The other end of the locking plate 42 is fork-shaped and its members are provided with insulated projections 49 and 50. Insulated projection 49 in one of its extreme positions serves to close circuit-closing springs 51, while projection 50 serves to release the armature 52 of locking magnet 53 from its catch 54. The armature 52 at its extreme end also carries an insulated projection adapted to close the springs 55. The locking plate 42 is provided with an 55

apertured vertical lug 56 through which rod 57 of the plunger 58 of solenoid 59 is passed. Referring now to the operation of the switch, it should be noted that the U-shaped frame is normally locked with its idle plungers in operative relation to an idle trunk, while the arm 36 to which the U-shaped frame is resiliently connected by the spring 74 is held in operative relation to a second 10 idle trunk. When the preselected trunk is seized, the U-shaped frame is released and under the action of spring 74, moves into alinement with the arm 36 where it is locked, whereupon operating circuits are closed to 15 move the arm 36 to preselect a second idle trunk. Assuming that the U-shaped frame is holding its idle plungers in operative relation to the first trunk of the group, in which case the brush 72 will be in engagement 20 with the first contact of the master switch bank 41 and that the arm 36 is in position before the second trunk of the group with its brush 40 in engagement with the second contact of the master switch bank 41, when 25 the subscriber located at 60 removes his receiver from the switch hook, line relay 61 is energized over a circuit which extends from grounded battery, relay 61, innermost circuit-closing springs 35, conductor 62, substantiation 60, conductor 63, outermost circuit-closing springs 35 to ground. Line relay 61 attracts its armature and completes a circuit through the pull down winding 33 of magnet 32. This circuit extends from grounded 35 battery, circuit-closing springs 48, conductor 64, conductor 65, pull down winding 33, front contact and armature of relay 61 to ground. The armature 31 of magnet 32 is attracted and engages the lug 30 of the plunger 30 individual to the calling line. This 40 moves the insulated knob 25 of the plunger 6 into the selected bank of contacts 26. The holding coil 34 is thereupon energized over a circuit which extends from grounded battery, holding coil 34, contact springs 66 and 67, conductor 68 to ground. This holding coil holds the plunger firmly in the contact bank until the ground on conductor 68 is removed when one of the parties replaces his 45 receiver at the close of the conversation. At the contact springs 69 and 70, an energizing circuit is completed for the trip magnet 15. This circuit extends from grounded battery, winding of trip magnet 15, conductor 71, brush 72 now in engagement with the first contact of master switch bank 41, conductor 73, spring 69, spring 70 to ground. The magnet 15 is energized and attracts its armature 16. The attraction of armature 16 moves the catch 18 out of engagement with the notch 14 which permits the locking plate with its associated frame 9 to move into alinement with the arm 36 under control of retractile spring 74. In its attracted position, armature 16 also closes the circuit-

closing springs 20 and completes a locking circuit for magnet 15 from grounded battery, resistance 75, springs 20, conductor 79, coil 21, to ground. When the arm 36 moves into alinement with U-shaped frame 8, the insulated knob 38 of angular extension 37 closes the springs 39. This serves to complete a circuit through starting relay 76, which circuit extends from grounded battery, winding 77 of the starting relay, conductor 78, 75 left and right-hand circuit-closing springs 39 to ground. Simultaneously a shunt circuit is completed about the locking winding of the trip magnet 15, which causes this magnet to retract its armature. This shunt circuit extends from grounded battery resistance 75, conductor 79, middle and right-hand circuit-closing springs of set 39 to ground. Trip relay 15 then retracts its armature to lock frame 8 before a preselected 80 trunk. The starting relay 76 when it attracted its armature, completed an energizing circuit for the trip magnet 46. This circuit extends from grounded battery, winding of magnet 46, conductor 83, armature 90 and front contact of starting relay 76 to ground. The trip magnet attracts its armature 45 and thereby withdraws the catch 44 from notch 43, thus allowing the locking plate to move under the tension of its controlling spring. The armature 45 at its knob 47 opens the contact springs 48, thus interrupting the energizing circuits of all 95 of the pull down coils. This prevents any plunger from operating until the locking 100 plate 42 with its associating member 36 is directly in front of a set of idle trunks. At the beginning of the cycle of operation of the switch when the brush 40 engages the first contact of the master switch bank 41, 105 the insulated knob 49 of the locking plate 42 brings the circuit-closing springs 51 into engagement. At the same time the starting relay 76 completes an energizing circuit for the lock magnet 53. This circuit extends 110 from grounded battery, magnet 53, circuit-closing springs 51, held in engagement by the knob 49 in its remotest position, conductor 80, armature and front contact of starting relay 76, to ground. Lock magnet 115 53 attracts its armature 52. This armature is held in attracted position by latch member 54, which causes the insulated end of armature 52 to close the springs 55, completing an energizing circuit for the solenoid 59. 120 This circuit extends from grounded battery, solenoid 59, conductor 81, circuit-closing springs 55 to ground. Solenoid 59 remains energized until at the close of the cycle of operation of the switch after the brush 40 125 has swept over the master switch bank 41, the knob 50 disengages the armature 52 from latch 54, whereupon the spring 84 moves the locking plate 42 to bring its knob 49 into engagement with the circuit-closing springs 130

51 and places the brush 40 into engagement with the first contact of master switch bank 41. The solenoid during its energization attracts its plunger 58 and thus serves to move 5 the locking plate 42 whenever this plate is disengaged from the catch 44.

It will thus be seen that the U-shaped frame 8 preselects an idle trunk, while the arm 36 serves to preselect a second idle 10 trunk. If the sets of contacts immediately adjacent to the sets before which the frame 8 is in operative relation for engagement is busy, this condition will be indicated by 15 ground on the related contact in the master switch bank 41. As soon as brush 40 engages any grounded contact, the winding 82 of relay 76 will be energized over the following circuit: grounded battery, winding 82, brush 40 and grounded contact of the 20 master switch bank. The attraction of the armature of relay 76 completes an energizing circuit for magnet 46, which magnet releases the locking plate 42, allowing the arm 36 to move into position before a set of idle 25 trunks. At the termination of the conversation, the subscriber at 60 replaces the receiver, thus interrupting the energizing circuit for line relay 61, whereupon the pull down coil of magnet 32 is deenergized. The 30 calling party on replacing his receiver, causes circuit changes at the succeeding selecting switches which remove ground from conductor 68, and interrupts the energizing circuit for the holding coil 34. The armature 31 of magnet 32 is retracted under the 35 action of its controlling spring. The plunger 6 is free to move and its retractile spring 29 serves to bring the notch 28 in the sector-shaped portion of the plunger into engagement 40 with the rib 11 of the frame 7.

It will be understood that this disclosure is merely illustrative of applicant's device, and that the invention is capable of many modifications and variations, which will be 45 limited only by the scope of the appended claims.

What is claimed is:

1. In a non-numerical switch, in combination, contacts serving as terminals of incoming lines and outgoing lines, automatic switching means for interconnecting said contacts, means for preselecting the contact of an idle outgoing line, and rotatable means for preselecting the contact of a second idle 55 outgoing line and for actuating said first-mentioned preselecting means.

2. In a non-numerical switch, in combination, sets of passive contacts, contact-makers mounted to interconnect said passive contacts, means for operating said contact-makers,

ers, means for preselecting sets of idle contacts, and means for preselecting second sets of idle contacts and for actuating said first-mentioned preselecting means.

3. In a non-numerical switch, a plurality 65 of sets of passive contacts, a plurality of contact-makers mounted to bring said sets of contacts into conductive relation, means controlling said contact makers for preselecting an idle set of contacts, and means 70 for preselecting a second set of contacts and serving to operate said first-mentioned preselecting means.

4. In a non-numerical switch, a plurality 75 of sets of passive contacts, a plurality of contact-makers mounted to bring said sets of contacts into conductive relation, a member mounted to normally place said contact-makers in operative relation to idle sets of contacts, a second member normally held in 80 operative relation to second sets of idle contacts and controlling said first-mentioned member, and means operating to move said second member when one of said sets of contacts becomes busy. 85

5. In a non-numerical switch, a plurality 90 of sets of passive contacts, a plurality of plungers mounted to bring said sets of contacts into conductive relation, a member normally positioning idle plungers in operative relation to idle sets of contacts, means for locking said member in such position before idle sets of contacts, a second 95 preselecting member to which said first-mentioned member is resiliently connected, means for operating said second member, and means for locking said second member in operative relation to idle sets of contacts.

6. In a non-numerical switch, a plurality 100 of sets of passive contacts, a plurality of plungers mounted to bring said sets of contacts into conductive relation, means for actuating said plungers, a member normally positioning idle plungers in operative relation to idle sets of contacts, a second member 105 to which said first mentioned member is resiliently connected and serving to move said first mentioned member, means for locking said first member in the position to which it is moved and for releasing said first member when a plunger has been actuated, means for operating said second member, and means operating to lock said second member in operative relation to idle sets of contacts when said first and second-mentioned members are out of alignment. 110

In witness whereof, I hereunto subscribe my name this 8th day of September, A. D. 1916.

CHARLES L. GOODRUM.
